GARMENT CONSTRUCTION

Perkins H. Bailey, New York, N. Y., assignor to
Talon, Inc., a corporation of Pennsylvania

Application December 23, 1939, Serial No. 310,719

2 Claims.

(Cl. 2-93)

This invention relates to garments and, in particular, to the provision therein of improved closure-forming means for forming a closure into which the garment may be packed or inserted for convenience when not in use.

It is an object of this invention to provide such garment closure-forming means which is extremely inexpensive, which is of simple form and slight bulk, and the provision of which, in a garment, may be accomplished without inconvenience to wearers of the garment.

It is a further object of this invention to provide such garment closure-forming means wherein in the closure formed thereby is substantially tubular and open, preferably, at both ends for facilitating packing or stuffing of the garment therein.

It is a further object of this invention to provide such garment closure-forming means which is independent of the garment construction, which may be detachably secured to the garment, and which is readily detachable therefrom for use independently thereof, as for a seat cover, a closure for other garments, and/or for washing or cleaning independently of the garment.

It is a further object of this invention to provide such garment closure-forming means incorporating pocket means adapted for receiving other garments or objects, which pocket means is so disposed with respect to the garment closure-forming means, as to be closed by formation of a garment closure by the garment closure-forming means.

It is a further object of this invention to provide such means which is readily, cheaply and conveniently applicable to various garment constructions previously or otherwise manufactured independently thereof.

These and other objects and advantages of the invention will appear from the following description taken in conjunction with the accompanying drawings which form a part thereof, and will be pointed out in the appended claims.

In the drawings:

Fig. 1 is a view illustrative of the application of one form of the invention to the inside of the rear of a jacket;

Fig. 2 is an enlarged fragmentary detail, in section, taken substantially on the line 2-2 of Fig. 1;

Fig. 3 is a view, in perspective, of the structure shown in Fig. 1, showing the garment packed in the garment closure-forming means illustrated in that figure;

Fig. 4 is a fragmentary detail, similar to Fig. 2,

illustrating a modification of the structure shown in Figs. 1 and 2;

Fig. 5 is a fragmentary view, in perspective, illustrating the application of a modified form of the invention to a garment similar to that shown in Fig. 1;

Fig. 6 is an enlarged fragmentary view, in section, taken substantially on the line 6-6 of Fig. 5; and

Fig. 7 is a view similar to Fig. 6, but illustrating a modified form of the structure shown in Fig. 6.

Former attempts at the provision of garment closure-forming means associated with garments of various types have resulted in diversified garment constructions. In some of these constructions the garment material formed the walls of the closure. The use of the closure-forming wall portion of the garment, for enclosing the garment, resulted in undesirable localized wear at that portion of the garment. This portion also became soiled long before equal soiling of the other garment portions and it was impossible to clean this soiled portion independently of the other garment portions.

In these garment constructions, where slide fastener stringers were secured directly to the garment material, for the formation of a garment closure, the necessary size of the container or closure to be formed required such placement of the slide fastener stringers as was highly undesirable from a point of convenience of the wearer. Furthermore, the garment closure-forming structure was integral with the garment and all of the constituent slide fastener stringers remained at all times upon the garment.

These known constructions required the packing or stuffing of the garment into one side only of the formed pocket-like garment closure which was, in many cases, extremely inconvenient and difficult. These constructions were, furthermore, substantially expensive and it was necessary that they be built into the garment at the time of its manufacture. According to the principles of this invention, all of the above disadvantages are totally obviated.

Referring to the drawings in detail and with reference particularly to Figs. 1, 2 and 3, wherein one preferred form of this invention is illustrated, it will be seen that the illustrated closure-forming means comprises a sheet or strip 11 of suitable material secured by stitching 12 to a wall or panel of the garment 10, which is shown as a jacket. As shown, the sheet or strip 11 is substantially rectangular, and the bottom edge 14

and top edge 15 are provided with complementary slide fastener stringers 16 and 17 respectively secured thereto in suitable manner, as by stitching 18. The stringers 16 and 17 each comprises stringer tapes having thereon rows of interlocking fastener members which are adapted for engagement to secure the top and bottom edges together whereby the sheet or strip 11 forms a substantially cylindrical closure or container, as shown in Fig. 3.

As shown in Fig. 1, one of the stringers is provided with the male element 19 of a separating end, while the other stringer is provided with the female portion 20 thereof. A conventional slider 21 is manually slidable on the stringers for engaging and disengaging the interlocking fastener members in known manner.

As is shown in Figs. 1 and 3, the side edges 22 and 23 of the sheet or strip 11 have the major portion thereof, at least, free of attachment to the garment 10 and, as will be readily understood, the garment enclosing closure formed by the member 11, as shown in Fig. 3, is open at each end, which materially facilitates packing or stuffing of the garment 10 within the closure formed by the sheet or strip 11.

It is preferable that the attachment of the sheet or strip 11 to the garment 10 be made at the inside of the garment at a portion thereof disposed substantially at the small of the back of the user. However, it is, of course, to be understood that other locations of the sheet or strip 11 with respect to the garment 10 are contemplated by me and may, in certain cases, be preferable.

As will be readily understood from Fig. 1, when the sheet or strip 11 is secured to the garment as shown, the transversely disposed edges 14 and 15 will lie within the garment above the lower edge of the tail portion of the jacket in such manner as to be imperceptible in the jacket when worn.

While the stitching 12 secures the garment closure-forming sheet or strip 11 permanently to the garment 10, it is contemplated by me that the sheet or strip 11 be detachably secured to the garment 10 by suitable known means such as a slide fastener comprising complementary slide fastener stringers 24 and 25 (Fig. 4), one of which is secured to the garment 10, as by stitching 26, and the other of which is secured to the sheet or strip 11 in suitable manner as by stitching 27. The slide fastener means comprising complementary stringers 24 and 25 is located between the edges 14 and 15 of the strip 11 and at a suitable point on the garment 10.

In the use of the garment 10 illustrated in Figs. 1 to 4 inclusive, the portion of the sheet or strip 11 above the stitching 12 and slide fastener comprising stringers 24 and 25 respectively, will overlie and overlap that portion of the sheet or strip 11 below the stitching 12 or the slide fastener. The respective portions of the sheet or strip 11 may thus move freely and accommodate themselves to the movements of the garment wearer.

When it is desired to enclose the garment 10 within the closure formed by the sheet or strip 11, as shown in Fig. 3, it is merely necessary to place the jacket inside out with the sheet or strip 11 on a substantially flat surface and roll the jacket partially toward the stitching 12 or the slide fastener 24, 25. The edges 14 and 15 are then brought over the rolled jacket and the stringers 16 and 17 are secured together in interlocking relationship by actuation of the slider 21.

as shown in Fig. 3. Thereafter, the portions of the garment 10 which remain outside the cylindrical garment closure formed by the sheet or strip 11 are stuffed inwardly from both open ends of the closure to form a package, as shown in Fig. 3.

To release the garment 10 from the closure, it is merely necessary to disconnect and separate the slide fastener stringers 16 and 17 at the bottom and top edges 14 and 15 of the sheet or strip 11 and thereafter to shake out the garment which will return substantially to the position illustrated in Fig. 1.

In the form of the invention illustrated in Fig. 4, when it is desired to remove the closure-forming sheet or strip 11 from the garment 10, it is merely necessary to disconnect the complementary slide fastener stringers 24 and 25 for removal of the sheet or strip 11. The removal of the closure-forming strip or sheet 11 makes possible the cleaning of this sheet or strip 11 independently of the garment 10 and makes possible its independent use for many purposes such as for a seat cover or for use as an independent container for articles of clothing or other articles.

In the embodiment of my invention illustrated in Figs. 5, 6 and 7, the garment closure-forming means comprises a sheet or strip 31 similar to the sheet or strip 11 and having the bottom edge 34 thereof provided with a slide fastener stringer 36 similar to the above-described slide fastener stringer 16 and the top edge 35 thereof provided with a slide fastener stringer 37 similar to the above described slide fastener stringer 17. A pocket-forming sheet or strip 38 has the bottom edge thereof aligned with and secured to the bottom edge 34 of the sheet or strip 31 and to the slide fastener stringer 36 which is also secured thereto. The side edges of the pocket-forming sheet or strip 38 are secured to the side edge portions of the sheet or strip 31 in suitable manner, as by stitching.

In order to facilitate carrying of the closure formed by the sheet or strip 31 and pocket-forming sheet or strip 38, suitable handle means in the form of a transverse strip 40 is secured at each end to the sheet or strip 31, as shown in Figs. 5 and 6. The garment closure formed by the sheet or strip 31 and attached pocket-forming sheet or strip 38 is secured to the garment 41 in the same manner in which the closure-forming sheet or strip 11 is secured to the garment 10, as described above, namely, by means of stitching 42, as shown in Figs. 5 and 6, or by means of a slide fastener comprising complementary slide fastener stringers 43 and 44 secured respectively to the garment 41 and the pocket-forming sheet or strip 38 in suitable manner as by means of stitching 45 and 46, as shown in Fig. 7.

From Figs. 5 to 7 inclusive, it will be readily understood that the intermediate pocket-forming sheet or strip 38, by means of its attachment to the sheet or strip 31, forms therewith a pocket open only at the top, between the sheet or strip 31 and the garment 41, and adapted to receive and enclose other garments and articles of clothing or the like such as water-proof pantaloons, gloves, mufflers, etc. which may be readily inserted in the pocket formed by the sheets or strips 31 and 38 when the slide fastener stringers 36 and 37 are disconnected, as shown in Figs. 5 and 6.

When it is desired to form a garment-receiving closure, it is merely necessary that the garment

be partially rolled toward the stitching 42 (Fig. 6), or the slide fastener comprising stringers 43 and 44 (Fig. 7), and the edges 34 and 35 of the sheet or strip 31 be brought together over the rolled garment and the stringers 36 and 37 connected to form a substantially cylindrical closure, open at both ends, within which the pocket formed by the sheets or strips 31 and 38 is disposed. Those portions of the garment 41 lying outside the closure defined by the sheet or strip 31 are thereafter stuffed inwardly into both open ends of the closure.

Thereafter, if it is desired to remove the garment from the closure, it is merely necessary to separate the fastener stringers 36 and 37 by actuation of the associated slide fastener slider, and to shake out the garment which will return substantially to the position shown in Fig. 5.

It will be readily understood that connection of the stringers 36 and 37 effectively closes the pocket formed by the sheets or strips 31 and 38, because of the location of the pocket within the closure formed by connection of the edges 34 and 35 of the strip 31.

In the form of the invention illustrated in Fig. 7, when it is not desired to retain the garment closure structure 31, 38 on the garment 41, it is merely necessary to disconnect the complementary slide fastener stringers 43 and 44 for the removal of the garment closure. Removal of the garment closure greatly facilitates cleaning of the garment closure independently of the garment 41 and makes possible its use for many purposes such as a seat cover in stadii and other places and/or its use as an independent container for other articles of clothing and other objects.

It is, of course, to be understood that the above-described structure is merely illustrative and in

nowise limiting and that I desire to comprehend within my invention all modifications included within the scope of the appended claims.

Having thus fully described my invention, what I claim as new and desire to secure by Letters Patent is:

1. In combination with a garment, a garment closure construction comprising a sheet of material having complementary slide fastener stringers secured to opposite edges thereof, means detachably connecting said sheet to said garment and comprising a slide fastener having one stringer thereof secured to said sheet intermediate said first-named slide fastener stringers and the other stringer thereof secured to said garment, said sheet being adapted upon connection of the complementary slide fastener stringers at opposite edges thereof to form a garment closure open at both ends.
2. In combination with a garment, a garment closure-forming structure comprising a substantially rectangular closure-forming sheet of material, complementary detachable connecting means attached to opposite longitudinal edges of said sheet, a pocket-forming sheet of material secured to said closure-forming sheet and having one edge free of attachment to said closure-forming sheet to form therewith a pocket, and complementary detachable connecting means on said last-named edge and said jacket respectively for detachably connecting said closure-forming structure to said garment, the complementary detachable connecting means on said sheet edges being connectible to form a garment closure open at both ends and said pocket being disposed within said closure when said garment is packed therein.

PERKINS H. BAILEY.
